UNITED STATES PATENT OFFICE.

JESSE VANDENBURGH AND JAMES A. GILKERSON, OF CORTLAND, N. Y.

SCREW-CUTTING MACHINE.

SPECIFICATION forming part of Letters Patent No. 251,322, dated December 20, 1881.
Application filed June 30, 1881. (No model.)

To all whom it may concern:

Be it known that we, JESSE VANDENBURGH and JAMES A. GILKERSON, citizens of the United States, residing at Cortland, in the county of Cortland and State of New York, have invented certain new and useful Improvements in Screw-Cutting Machines; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

In said drawings, Figure 1 represents a central longitudinal section of the die-carriers, supports, and actuating mechanism, showing the details of construction, combination, and adjustment which are peculiarities of our invention. Fig. 2 represents an end view of the chuck or sectional die-holders or carriers. Fig. 3 represents a plan view of some of the important parts, and Fig. 4 represents in detail the construction of the actuating clutch-lever.

In the several figures the same letters of reference indicate like parts.

Our invention relates more particularly to cutting threads upon bolts and rods, and its object and purpose is to do the same easily and readily and allow the bolt or rod to have its thread cut and the dies to be disengaged therefrom without running them back off the thread so cut; and our invention consists in the arrangement and combination of the herein described and shown mechanism, whereby the foregoing objects and purposes are accomplished.

We now proceed to describe in detail our invention with reference to the said drawings.

A represents the hollow mandrel, to which power is applied through the medium of the pulley B, which runs loose upon the mandrel when the dies are not doing labor. The front side of the hub of the pulley has clutch-teeth, which engage in the cam and clutch-sleeve C, which slides on the mandrel A, and is guided by the feather-key or spline D. This sleeve C and the hub of pulley B are both inclosed, and run in the front or main bearing, E, thereby preventing the noise which would be pro-

duced if the clutches were not covered, and also excluding all particles of dirt and chips, which would get in and binder the free working of the machine. Upon the end of the mandrel A is the flange or face-plate F, either forged solid or fixed thereto, to which flange the die-carriers G are pivoted by means of a screw stud or rivet, H, each carrier having in the opposite end a pin, I, which, engaging in the cam or angular slot J in the cam-plate K, fastened to the clutch-sleeve C, form the mechanism by which the adjustments are made. The dies L are fastened substantially to the carriers G in any suitable manner; or they may be made a part of and solid with the carriers G, it being immaterial how they are made, as long as they form a part of and move only in direct connection with the sectional carriers G.

The operation of the machine is substantially as follows: The drawings represent the machine in readiness to work the clutch-sleeve C, being engaged in the clutch upon the hub of the pulley, and the pin I being in the straight part of the cam-slot J. The blank being brought up to and pushed into the threading-dies L, it is drawn into them and threaded until the required length of thread is obtained, when, either by an attendant or by automatic mechanism, the sleeve C is moved toward the head or flange F, causing the cam-slots to move the pins I, thereby causing the carriers G to open, relieving the screw, when it is drawn out of the dies. The next operation is to throw the clutch which closes the dies into gear and repeat the operation.

It will be noticed that when the dies are in position for operation the strain all comes upon the side of the straight part of the slot J, and to compensate for the wear upon this part, it being the only point with which wear will cause any variation in the size of the screw when threaded, the dovetailed piece M, made of hard steel, is fastened into the plate K, and may be replaced by another at a trifling cost. There being no motion between the pin I and the dovetailed piece M when the dies are working, there will be very little wear on either of them.

Now, for operating the clutch and cams the lever and ring shown in Fig. 4 are used. W represents the lever, and P and Q the ring,

which latter is made substantially as follows: The pieces for the ring Q and P are made in separate sections, which unite through the bosses or hubs R, and are fitted together and riveted. It is then bored out to fit the groove S, turned into the clutch-sleeve C, and an oil-hole, T, is drilled longitudinally through one of the bosses R, for the purpose of supplying oil to the groove S in the clutch-sleeve C, 5 said bosses being turned to fit holes which are drilled into the ends of the lever-arms N and O, which, when put together, form the bifurcated lever W, which moves the clutch-sleeve C, and at the same time operates the adjustment of the dies and die-carriers G.

It is obvious that a clutch-lever and ring made in this manner will save a great deal in cost and wear, as it reduces the parts to the least possible number and saves much time and 10 labor in construction. U is a bearing, which supports the back end of the mandrel A, and V V are thrust-collars, which hold the mandrel and keep it from moving endwise through the pulley-hub B and bearing U.

20 For obtaining variations of speed a gear-wheel may be substituted for the pulley B, having a hub made similar to the pulley-hub 25

and driven by a counter-shaft having a cone-pulley upon it.

Having described our invention, what we claim as new, and desire to secure by Letters Patent, is—

1. The cutting-dies and carriers and the carrier-shifting cams, combined with mechanism C I, &c., for moving said cams and throwing 35 the cutting-dies in or out of operation as the carriers are thrown in or out of connection with the power, as specified.

2. The plate K, having the dovetailed hardened wearing-piece M, combined with the clutch-shifter and the die-carriers, as and for the purposes set forth.

3. The plates K, having inclined slots J, the wearing-pieces M, and pins I, combined with the clutch, clutch-shifter, the die-carriers, the 45 dies, and the power-shaft, as and for the purposes set forth.

In testimony whereof we affix our signatures in presence of two witnesses.

JESSE VANDENBURGH.
JAMES A. GILKERSON.
